ROLL GRINDER AND POLISHER

William Henry Wilkes, Florence, N. J., assignor
to Wm. R. Thropp & Sons Co., Trenton, N. J.,
a corporation of New Jersey

Application August 6, 1946, Serial No. 688,789

10 Claims. (Cl. 51—252)

1 This invention relates to new and useful improvements in roll grinding and polishing devices, and more particularly to devices for polishing and resurfacing rolls and like mills such as, for example, those used in numerous manufacturing and industrial processes.

In the manufacture and processing of many products the material or materials are passed between cooperating pairs of rolls suitably spaced apart and positioned to perform a particular operation upon the materials passed therebetween.

In most cases it is essential that the surface of these rolls be maintained smooth and true, and this requires that the rolls be ground and polished from time to time as required. Furthermore, it is desirable that this refinishing of the surface of the rolls be carried out at the place where the rolls are installed in order to save the time that otherwise would be lost to dismantling the mill and returning the rolls to the factory where made for such refinishing.

With the foregoing in mind, the principal object of the present invention is to provide a novel grinding and polishing device for rolls which is portable and may be used to refinish and resurface rolls in the field without removing the rolls or dismantling the mill in which incorporated.

Another object of the invention is to provide a novel grinding and polishing device of the character set forth which may be readily and easily applied to the rolls of a mill to resurface or refinish the same and then be quickly and easily removed therefrom.

Another object of the invention is to provide a grinding and polishing device of the stated type having novel features of construction and arrangement for securing and adjusting therein the abrasive members.

A further object of the invention is to provide a novel and improved grinding and polishing device of the type described embodying relatively opposed sets of abrasive members together with means for controlling contact thereof with the surfaces of the rolls.

Still a further object of the invention is to provide a novel grinding and polishing device having the characteristics and features set forth which is of relatively simplified and inexpensive construction and highly effective and efficient in operation and use.

These and other objects of the invention and the various features and details of the construction, operation and use thereof are hereinafter

fully set forth and described with reference to the accompanying drawings in which:

Fig. 1 is an elevational view showing a rolling mill having operatively associated therewith a grinding and polishing device made according to the present invention;

Fig. 2 is an enlarged fragmentary sectional view taken on line 2—2, Fig. 1;

Fig. 3 is an enlarged sectional view taken on line 3—3, Fig. 2, and

Fig. 4 is an exploded perspective view showing the operative relationship of certain parts of the device illustrated in Fig. 3.

Referring now more particularly to the drawings, the present invention is shown as applied to an ordinary roll mill wherein reference numerals 1 and 2 designate the standards of the mill frame, and numerals 3 and 4 designate the upper and lower rolls, respectively.

With reference more particularly to Fig. 2 of the drawings, a grinding and polishing device made according to the present invention comprises a pair of carriers 5 which are constructed and arranged for disposition at opposite sides of the bite of the upper and lower rolls 3 and 4 in the relationship shown in the drawings. Each of the carriers 5 includes a pair of oppositely arranged abrasive block supporting portions 6 of arcuate configuration conforming substantially to the curvature of the mill rolls 3 and 4, respectively, and disposed centrally and outwardly of these support portions 6 is an integral vertically extending flange portion 7.

The two carriers 5 are retained in the positions shown at opposite sides of the bite of the rolls 3 and 4 by means of a tie-rod or the like 8 which extends between the said rolls and through suitably aligned passages 9 provided in the flanges 7 of the carriers 5. The outer end portions of the tie-rod 8 are threaded as indicated at 10 and 11, respectively, to receive thereon an adjustable stop member 12 and an adjusting hand wheel 13. The mid portion of the tie-rod 8 is reduced in diameter as shown at 14 to receive sleeve or tubular shield 15 of plastic or other suitable material

that will serve to prevent damage to the rolls such as scratching or scarring of the surfaces thereof being ground or polished.

As shown in Fig. 2 of the drawings, each of the arcuate support portions 6 of the carriers 5 is provided with a pair of recesses 16 adapted to removably receive therein abrasive blocks or the like 17 selected according to the particular grinding or polishing operation to be performed. These recesses extend horizontally or trans-

versely of the carriers 5 in circumferentially spaced relation with respect to the arcuate configuration of said supports 6 and the rolls 3 and 4. It is to be noted with reference to Fig. 3 that in the direction circumferentially of the rolls 3 and 4 the recesses 16 are of substantially greater width than the abrasive members 17 and that while the inner wall 18 of each recess 16 lies in a plane perpendicular to the side faces 6a and 6b of the support portions 6, the outer wall 19 of each recess is angularly disposed as indicated to provide a tapered space between it and the block 17 for the reception of a wedge element 20 that serves to clamp the abrasive block and retain it firmly with the recess 16 against accidental displacement.

The wedge element 20 may be loosened or tightened with respect to the abrasive block 17 by means of a screw or the like 21 threaded into a tapped bore 22 arranged as shown in the support portion 6 and counterbored as indicated at 23 to receive the head 24 of the screw 21 which also engages within a relatively shallow arcuate recess 25 provided in the wedge element 20. By this construction it will be observed that as the screw 21 is threaded inwardly or outwardly of the bores 22 and 23 so also will the wedge element 20 be moved inwardly or outwardly with respect to the recess 16 and the member 17 thereby clamping the latter more firmly in the carrier or releasing it, as the case may be.

The inner face of each abrasive block 17 is adapted to seat or abut against a backing plate 26 disposed in the recess 16 and provided with ears 27 at its opposite ends which outwardly lap the side faces 6a and 6b of the carrier support portions 6 and are provided with radially extending slots 28 that slidably receive screws or the like 29 which limit the extent of radial movement of the plate 26 and may be tightened to secure the said plate in a selected position within said limits. Pairs of set screws 30 having lock nuts 31 are mounted in the support position 6 of the carriers 5 at opposite sides of the flange 7 thereof and arranged in the manner shown to engage inwardly against the backing plate 26 as shown in the broken away and sectional portions of Fig. 2 of the drawings.

Thus it will be apparent that the several screws 21, 29 and 31 may be manipulated to variously position the abrasive blocks 17 radially within their recesses 16 as the particular job may require, and that the screws 21 may be manipulated to release the blocks 17 for removal and replacement or substitution and then be securely clamped in fixed position in the recesses 16 of the carriers 5 as required or desired.

The device may be readily and easily mounted in cooperative association with a pair of rolls, for example, merely by removing the hand wheel 13 and the adjacent carrier 5 from the tie-rod 8 and then passing the latter between the rolls 3 and 4 from the other side of the bite thereof after which the removed carrier may be replaced together with the hand wheel 13. Assuming that the abrasive blocks 17 are properly positioned within the recesses 16, the rolls 3 and 4 may be rotated and when up to speed the hand wheel 13 may be adjusted to place the several abrasive blocks 17 into contact with the surfaces of the rolls 3 and 4 at the pressure desired. In the event only one of the rolls is to be surfaced the abrasive blocks 17 associated with the other roll may be replaced with plain hard wood blocks, or the like.

Grinding or polishing of the rolls throughout their length is effected by traversing the device lengthwise between the rolls across the entire faces thereof and this may be accomplished manually or by suitable mechanical means which form no part of this invention. The device is extremely flexible and substantially universal in its applications and may be employed effectively for refinishing or resurfacing both straight and crown face rolls.

From the foregoing it will be apparent that the present invention provides a novel grinding and polishing device which is portable and may be used effectively to refinish and resurface rolls in the field. The invention also provides a device of the stated type which embodies novel features of construction and arrangement for securing and adjusting therein the abrasive members. The invention further provides a novel grinding and polishing device having the features and characteristics herein described which is of relatively simplified and inexpensive construction and highly effective and efficient in operation and use.

While a particular embodiment of the invention has been illustrated and described herein, it is not intended to limit the invention to such disclosure, and changes and modifications may be made therein and thereto within the scope of the claims.

I claim:

1. In a portable grinding or polishing device for rolls, a pair of carriers adapted to be positioned at respectively opposite sides of the bite of a pair of rolls and having arcuate support portions arranged substantially to conform to the curvature of the rolls, and means associated with said carriers and arranged to extend between said rolls to support the carriers relative to the rolls.

2. In a portable grinding or polishing device for rolls, a pair of carriers adapted to be positioned at respectively opposite sides of the bite of a pair of rolls and having arcuate support portions arranged substantially to conform to the curvature of the rolls, abrasive members carried by said carrier support portions and arranged to engage the surfaces of said rolls, means arranged to extend between the rolls and interconnecting said carriers to support the same relative to the rolls, and means operable to adjust the said carriers relative to one another and thereby regulate the contact of said abrasive members with said rolls.

3. In a portable grinding or polishing device for rolls, a pair of carriers adapted to be positioned at respectively opposite sides of the bite of a pair of rolls and having arcuate support portions arranged substantially to conform to the curvature of the rolls, abrasive members adjustably carried by said carrier support portions and arranged to engage the surfaces of said rolls, a tie-rod arranged to extend between the rolls and interconnecting said carriers to support the same relative to the rolls, and means on said tie-rod manually operable to adjust the said carriers relative to one another and thereby regulate the contact of said abrasive members with said rolls.

4. In a portable grinding or polishing device, a pair of carriers adjusted to be positioned at opposite sides of the bite of a pair of rolls and having arcuate support portions substantially conforming to the curvature of the rolls, said support portion having recesses therein each defined in part by relatively spaced wall portions

one of which is disposed at an angle to the other wall, an abrasive member in each recess, a wedge shaped member in each recess intermediate the abrasive member and said angularly disposed wall to clamp the abrasive member therein, means to secure said wedge member in clamping position relative to said abrasive member, a tie-rod arranged to extend between said rolls and interconnecting said carriers to support the same relative to said rolls, and means to adjust the carriers relative to one another and thereby regulate contact of said abrasive members with the surfaces of said rolls.

5. In a portable grinding or polishing device, a pair of carriers adjusted to be positioned at opposite sides of the bite of a pair of rolls and having arcuate support portions substantially conforming to the curvature of the rolls, said support portion having recesses therein, an abrasive member in each recess, a member to clamp the abrasive member therein, a tie-rod arranged to extend between said rolls and interconnecting said carriers to support the same relative to said rolls, and means to adjust the carriers relative to one another and thereby regulate contact of said abrasive members with the surfaces of said rolls.

6. In a portable grinding or polishing device, a pair of carriers adjusted to be positioned at opposite sides of the bite of a pair of rolls and having arcuate support portions substantially conforming to the curvature of the rolls, said support portion having recesses therein, an abrasive member in each recess, a clamp member to secure the abrasive member therein, a tie-rod arranged to extend between said rolls and interconnecting said carriers to support the same relative to said rolls, and a threaded member associated with each of said carrier support portions and engaging said clamp member operable to advance and retract the latter relative to said abrasive member for respectively securing and releasing the latter within said recess.

7. In a portable grinding or polishing device for rolls, a pair of carriers adapted to be positioned at respectively opposite sides of the bite of a pair of rolls and having arcuate support portions arranged substantially to conform to the curvature of the rolls, abrasive members carried by said carrier support portions and arranged to engage the surfaces of said rolls, means operable to predeterminedly position said abrasive members individually within said slots radially with reference to an adjacent roll, means to clamp each of said abrasive members in such predetermined

position, means arranged to extend between the rolls and interconnecting said carriers to support the same relative to the rolls, and means operable to adjust the said carriers relative to one another and thereby regulate the contact of said abrasive members with said rolls.

5 8. In a portable grinding or polishing device for rolls, a pair of carriers adapted to be positioned at respectively opposite sides of the bite of a pair of rolls and having support portions for abrasive members disposed adjacent the surfaces of said rolls, and means arranged to extend between the rolls and interconnecting said carriers to support the same relative to the rolls.

10 9. In a portable grinding or polishing device for rolls, a pair of carriers adapted to be positioned at respectively opposite sides of the bite of a pair of rolls and having support portions for abrasive members disposed adjacent the surfaces of said rolls, a tie rod arranged to extend between the rolls and interconnecting said carriers to support the same relative to the rolls, and means on said tie rods manually operable to adjust the said carriers relative to one another and the surfaces of said rolls.

15 20 10. In a portable grinding or polishing device for rolls, a pair of carriers adapted to be positioned at respectively opposite sides of the bite of a pair of rolls and having support portions for abrasive members disposed adjacent the surfaces of said rolls, abrasive members carried by said support portions and arranged to engage the surfaces of said rolls, a tie rod arranged to extend between the rolls and interconnecting said carriers to support the same relative to the rolls, and means on said tie rods manually operable to adjust the said carriers relative to one another and said rolls.
